PROCESS FOR CRACKING PETROLEUM HYDROCARBONS

Walter M. Cross, Kansas City, Mo., assignor to
Gasoline Products Company, Inc., New York,
N. Y., a Corporation of Delaware

Application May 9, 1929. Serial No. 361,632

2 Claims. (Cl. 196—58)

This invention relates to improvements in the process and apparatus for cracking petroleum hydrocarbons and refers more particularly to a process in which the oil, after being brought rapidly to a cracking temperature, is maintained throughout the necessary time period to consummate the cracking at temperatures substantially at or slightly below the cracking temperature. The novelty in the invention lies primarily in the maintaining of the oil in the zone of reaction at temperatures not to exceed 100° F. below the cracking temperature or at temperatures sufficiently high to prevent the agglutination of the chemical condensation products formed in the oil.

The process also offers an operation by means of which carbon troubles usually accompanying oil cracking are substantially eliminated because the chemical condensation products formed, which consist of small globular bodies, are held in suspension in the liquid, coursing through the apparatus and this liquid is traveling at a sufficient velocity and with turbulence which maintains any separated bodies in suspension in the hydrocarbon menstruum.

Fig. 1 is a diagrammatic showing of the apparatus in which the process may be carried on. Referring to the drawing: at 1 is shown a furnace divided into compartments 2 and 3 by a bridge wall 4. Upon the sides and ceiling of the compartment 2 are arranged heating tubes 5 which are subjected to the heat of the combustion gases produced by burning fuel by means of a burner 6. In the adjacent compartment 3 is a bank of tubes 7 which are subjected to convection heat of the combustion gases passing over the bridge wall 4.

It will be noted that the cracking tubes in the chamber 2 are subjected primarily to radiant heat energy, while the bank of tubes 7 receives principally convection heat. The tubes 5 arranged upon the reflecting surfaces of the compartment 2 and on the ceiling of compartment 3 are connected in series to form a continuous coil. These tubes are connected by a transfer line 8 to the tube bank 7.

Connected to the discharge end of the tube bank 7, by means of a transfer line 9, is evaporator 10: interposed in the transfer line 9 is a pressure reduction valve 11. The evaporator has a liquid draw-off line 12 at the bottom, controlled by a valve 13. Vaporized overhead material passes off through the pipe 14 and is introduced near the bottom of the bubble tower 15. The bubble tower, or fractionator, has a

bottom liquid draw-off line 16, controlled by a valve 17, and a vapor draw-off pipe 18, which is controlled by a valve 19. The vapor line 18 is connected to a condenser coil 20, positioned in a condenser box 21, which is supplied with a suitable liquid cooling medium. The discharge end of the condenser coil, designated as 22, leads to a gas separator 23, which is equipped with a gas relief line 24, regulated by a valve 25 and a liquid draw-off line 26, controlled by a valve 27.

In the furnace any suitable type of fuel is used, either powdered coal, oil, gas, or a mixture of these fuels. The air supplied to the burner is introduced through the duct 28 and is forced by means of a fan 29 through an air preheater 30 in heat exchange relation with the flue 31, through which the spent combustion gases are discharged from the furnace. The heated air is then directed through the pipe 32, by means of which it is supplied to the burner.

Describing now the operation of the process. Charging stock from any suitable source, consisting of petroleum hydrocarbon suitable for cracking purposes, including kerosene, gas oil, fuel oil, or derivatives thereof, is supplied through the pipe 33 and is circulated through a preheating coil 34, positioned in the upper part of the bubble tower. The preheated oil is then directed by means of a pipe 35 to the cracking tubes 5, positioned in the chamber 2. In the cracking tubes, the oil is raised rapidly to a cracking temperature so that, on being discharged from the cracking tubes through the discharge line 8, the temperature has been raised to 700°—1000° F., depending upon the character of the oil undergoing treatment and the time allowed for cracking. The relation of the heating surface of the radiant tubes designated as 5 in the drawing to the convection bank designated as 7 is approximately as 2—1. Also the tubes in the convection bank are arranged so that the oil, in traveling therethrough, passes in a direction concurrently to the direction of the combustion gases, that is, from the top downwardly.

After passing through the reaction tubes, or convection bank, the oil is discharged through the pipe 9 into the evaporator. At the valve 11 the pressure is reduced and, with this reduction of pressure, there is a separation of vapors and liquid, due to the contained heat in the oil and the pressure reduction. At a point near the discharge of the convection bank is a pipe connection 36 by means of which a cooler medium may be introduced from any convenient extraneous source through the pipe 37, pump 38, and con-

necting pipe 36. A cooling medium such as steam, hydrocarbon oil of any suitable characteristic, or other cooling liquid may be used.

In the evaporator, a portion of the highly heated material flashes into vapor and passes off through the pipe 14, entering the bubble tower near its bottom where the vapors are fractionated, the lighter portion passing overhead and the heavier or higher boiling point products being drawn off through the pipe 16 and recirculated, by means of the pump 39, to the cracking tubes 5. The heavy liquid unevaporated in the container 10 is drawn off through the pipe 12 and diverted to fuel oil storage.

15 The overhead material from the bubble tower is passed through the condenser 20 and collected as distillate and gas in the separator 23 where proper separation of the constituents is effected.

20 The amount of reflux condensate or recycle stock returned from the bubble tower to the cracking tubes is determined by the amount of dephlegmation necessary which, in turn, is dependent upon the character of the oil undergoing treatment.

25 The temperature contemplated in the cracking tubes ranges from 700°-1000° F., the maximum temperature being attained in the discharge or transfer line 8 which connects the radiant tubes or cracking tubes with the convection bank or reaction tubes. In the reaction zone, which constitutes the convection bank of tubes 7, the temperature is not permitted to fall more than 100° below the maximum temperature in the cracking tubes 5. This decrease in temperature of approximately 100° has been found to be approximately the decrease in temperature which has no particular effect upon the agglutination or combination of the molecular particles of the condensation product accumulating in the oil during the cracking reaction.

40 The chemical condensation products formed during the cracking operation consist of small globular bodies held in suspension in the liquid cracking stock as it courses through the tubes in the cracking apparatus. These globular bodies, at the beginning of the cracking, are relatively sparsely scattered through the oil and, as the oil cracking proceeds by longer exposure to the cracking temperature, they become more and more abundant but, under the high temperatures maintained, do not readily stick together nor have a tendency to agglutinate. Since the temperature of the oil in which they float or are held in suspension remains at or slightly below the temperature at which these condensation products were formed, the particles seem to remain as separate entities, and have no tendency to agglutinate or stick together. The temperature may not, however, be decreased materially more than 100° before there is perceived an immediate tendency upon the part of the particles to accumulate.

45 The particles as formed are so small that it is necessary to see them with a high powered microscope and, when viewed in this manner, have a decided Brownian movement. The decrease in temperature necessary to cause the particles to agglutinate or become sticky and have a tendency to adhere to one another differs somewhat with 50 the different oils and somewhat with the temperatures necessary to crack the particular types of oils. If the temperature is reduced from slightly below the range, which is approximately 100°, these condensation products become sticky 55 and the little globular bodies composing them

gradually adhere to one another until their molecular weight is such that they are deposited or settle on to the container in which the oil is being held, or through which it is being passed.

56 In normal cracking operations utilizing heating coils and a separating or reaction chamber, the reduction in temperature in the separating chamber is materially in excess of 100°; consequently there is a rapid formation or accumulation of the hydrocarbon condensation products and considerable quantities of these condensation products are deposited.

60 The condensation products mentioned above are formed and are deposited in the usual cracking operation, and are ordinarily known in the petroleum industry as carbon; but it is not really a true carbon, but is a chemical condensation product which has a very high percentage of carbon and a low percentage of hydrogen in its molecules and also has a relatively high molecular weight.

65 In the present process, after the cracking operation and reaction period have been completed, there is a reduction of pressure and an immediate cooling of at least 250° or more below the cracking temperature, there is insufficient time allowed for the particles to become agglutinated and there is no precipitation of carbon.

70 In carrying out the process herein described, it is essential to prevent any considerable cooling of the cracking oil during the reaction or cracking periods. As suggested, at the end of the reaction period or time there is provided a means of sudden chilling of the oil to temperatures in excess of 250° and normally 350° or 100 more below the cracking temperature. The cooling and accompanying vaporization produce violent agitation and there is not sufficient time allowed for any agglutination of the particles to occur while the actual cooling takes place, thus 110 the globular particles will not adhere to each other and become sufficiently heavy to settle out.

75 While it is not possible to prevent all agglutination or accumulation of the separate particles, it can be prevented to such an extent that a cracking plant may be operated for ninety days or more, compared with the normal ten day period when this agglutination of the particles is allowed to take place in a relatively quiescent pool of oil and particularly when the temperature of the oil 120 is permitted to decrease more than the temperature range above noted, which has been found to be approximately 100° F. When the temperatures are permitted to go below this range, the 125 particles will immediately become sticky and tend to rapidly agglutinate, forming bodies which are deposited and are known in the industry as free carbon.

80 Inasmuch as in many very successful cracking processes, the time required for cleaning the apparatus, including the settling tanks, etc. may occupy as much at 10-20% of the total operating time, whereas in this method the cleaning operation may readily be reduced to 1-2% of the total 130 operating time, the present process offers a very great saving, particularly in view of the fact that the type of apparatus used may be constructed with considerable less expenditure than where 135 large separators or reaction chambers are supplied. The pressure maintained upon the cracking and reaction zones ranges from 500-1000 pounds per square inch and, under normal operation the pressure will be maintained at from 700-900 140 pounds, so that a substantial portion of the oil 150

passing through the system is maintained in the liquid phase.

The addition of a cooling medium, such as hydrocarbon, in the reaction zone, near the outlet thereof, is to facilitate and increase the rapidity with which cooling of the oil is carried on with a reduction of pressure. The introduction of a cool hydrocarbon near the discharge of the reaction period reduces the temperature below that point at which stickiness in the hydrocarbon particles is produced. The fact that these particles can be more or less rapidly frozen within the oil body so that they remain in a very finely dispersed condition with no tendency towards agglutination eliminates from the operation carbon difficulties which are inherent to liquid vapor phase cracking processes in use at the present time.

I claim as my invention:

1. A process of cracking hydrocarbon oil comprising the steps of passing oil through a section of a continuous coil in a heating zone, effecting combustion for said heating zone and subjecting the oil during substantially its entire travel through said section of the continuous coil to the radiant heat of combustion whereby it is rapidly brought to a cracking temperature, then passing the oil through another section of the coil in a second heating zone where it is subjected to convection heat from combustion gases derived from said first heating zone controlled to maintain the oil at a cracking temperature lower than the

cracking temperature attained by it in said first heating zone, then passing the oil through another section of the coil in the second heating zone where the temperature of the oil is rapidly decreased by the introduction of a cooling medium into the oil, and removing and vaporizing the oil.

2. A process of cracking hydrocarbon oil comprising the steps of passing oil through a section of a continuous coil heating zone, effecting combustion for said heating zone and subjecting the oil during substantially its entire travel through said section of the continuous coil to the radiant heat of combustion whereby it is rapidly brought to a cracking temperature, then passing the oil through another section of the coil in a second heating zone where it is subjected to convection heat from combustion gases derived from said first heating zone controlled to maintain the oil at a cracking temperature lower than the cracking temperature attained by it in said first heating zone, and not more than 100° F. therebelow so as to substantially prevent hydrocarbon condensation products formed during cracking from agglutinating, then passing the oil through another section of the coil in the second heating zone where the temperature of the oil is rapidly decreased by the introduction of a cooler hydrocarbon oil into the oil and removing and vaporizing the oil.
